(57) **CLAIM**

The ornamental design for a “domed container lid”, as shown and described.

DESCRIPTION

FIG. 1 is a perspective view of a domed container lid which embodies my new and original design therefor;
 FIG. 2 is a top plan view of thereof;
 FIG. 3 is a front elevational view thereof;
 FIG. 4 is a left side elevational view thereof, the right side elevational view being substantially a mirror image thereof;
 FIG. 5 is a rear elevational view thereof;
 FIG. 6 is a bottom plan view thereof; and,
 FIG. 7 is an environmental perspective view thereof, and wherein the dashed line representation of a container therein forms no part of the claimed design.
